ICE CREEPER

Anna Pikulik, Chicago, Ill.

Application September 15, 1938, Serial No. 229,991

1 Claim. (Cl. 36—62)

The present invention relates to ice creepers and has for its main object the provision of an antislipping device consisting of an oblong plate having an indented outer surface, with means at the ends of the plate to engage a shoe sole for maintaining the device in engagement with the shoe, with means provided at said oblong plate to frictionally engage the shoe sole for preventing the displacement or shifting movement of the plate on horizontal plane.

A still further object of the present invention is the provision of an ice creeper of the character indicated and which may be provided with shoe sole engaging means, whereby the use of unsightly straps may be entirely eliminated.

A still further object of the present invention is the provision of an ice creeper of the character indicated which may be very simple in construction, and which could be made by one or two simple machine operations, and the manufacture of which could be comparatively inexpensive.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application and in which like designating characters refer to corresponding parts throughout the several views,

Fig. 1 is a perspective bottom view of the shoe indicated by dotted lines with the ice creeper in operative position therewith, the ice creeper being shown in full lines;

Fig. 2 is a front elevational view of the shoe with the ice creeper shown in a position immediately prior to the attachment thereof with the shoe;

Fig. 3 is a similar view with the ice creeper attached to the shoe, the dotted lines of the ice creeper indicating an intermediary position during the attaching procedure thereof to the shoe;

Fig. 4 is an enlarged bottom elevational view of the ice creeper;

Fig. 5 is an elevational edge view of the ice creeper partly in section; and

Fig. 6 is an enlarged fragmentary cross-sectional view and longitudinally of the ice creeper, with a fragmentary cross-sectional view of a shoe with the ice creeper in attachment therewith.

Referring in detail to the present drawing there is shown an ice creeper consisting of an oblong plate 10 which may be of any desired shape and

configuration. Integrally formed at each end of said plate 10 is an upright extension generally indicated by 11 and which comprises an outwardly disposed body portion 12 immediately projecting from plate 10, and an inwardly disposed hook portion 13, said body portion 12 and hook portion 13 defining the letter S on vertical cross-section as is clearly seen in Fig. 6.

Struck out in plate 10 and projecting outwardly therefrom is a plurality of teeth or spurs 14. In the proximity of each end of plate 10 and adjacent extension 11 is an inwardly projecting spur or tooth 15.

In the operative association of the ice creeper with the shoe, said plate 10 is adapted to be positioned transversely of the shoe sole 16 or shoe 17, with teeth 15 frictionally engaging the lateral marginal portions of the sole 16 for preventing sliding or creeping movement of plate 10 on a plane coextensive with shoe sole 16, as is seen in Figs. 3 and 6. The outer edges of shoe sole 16 are adapted to be positioned within the recesses defined by the outwardly bulging body portions 12 of extensions 11, while hooks 13 being adapted for positioning within recesses defined by the marginal edge of shoe sole 16 and the body portion of the shoe. When said hooks 13 remain within said recesses defined by the sole and body portion of the shoe as seen in Figs. 3 and 6, the disengagement of the ice creeper on transverse plane 30 through the shoe will be entirely prevented.

Plate 10 and particularly extensions 11 are made of springy resilient metallic material so as to cause hooks 13 to spring within the said recesses when the ice creeper is applied to the shoe in the position seen in Fig. 3. Fig. 2 illustrates the mode of applying the ice creeper to the shoe, and shows the ice creeper in a preliminary adjusted position with the shoe, showing one tooth 15 and the adjacent hook 13 engaging one lateral edge of the shoe sole, with the opposite tooth 15 and its adjacent hook 13 in a preliminary position prior to engagement of the latter with the shoe sole. To engage the latter hook 13 with the adjacent marginal portion of the shoe sole, the adjacent hook 13 is manually sprung outwardly, the position illustrated by dotted lines in Fig. 3, so that said hook 13 may clear the outer edge of the marginal portion of the shoe sole in order to bring the adjacent hook 13 within the recess defined by the shoe sole 16 and the body of the shoe 17, the position shown in full lines in Fig. 3.

From the hereinabove description it will be seen that the device herein disclosed is simple in construction, which may be very inexpensive to 55

manufacture, and which is capable of efficient engagement with the shoe, without the employment of cumbersome and unsightly straps, and which may therefore quickly be applied to the 5 shoe in the event of necessity to use the same upon the shoe.

While there is described herein a preferred embodiment of the present invention, it is nevertheless to be understood that minor changes may 10 be made therein without departing from the spirit and scope of the invention as claimed.

What I claim as new is:

An ice creeper comprising an elongated plate of springy sheet metal adapted for positioning 15 upon the face of a shoe sole transversely of the

latter, upwardly projecting extensions integral with the ends of said plate and having terminal hooks, said hooks being curved inwardly and then upwardly and outwardly for engagement over the shoe sole at opposite sides of the latter by mere 5 upward pressure on the ends of said plate to retain the ice creeper on the shoe, a plurality of spurs struck downwardly from the body of said plate, and a plurality of spurs struck upwardly from the body of said plate and adapted to bite 10 into the shoe sole when the ice creeper is applied to the shoe for preventing forward or rearward shifting movement of said plate relative to the shoe sole.

ANNA PIKULIK. 15
